UNITED STATES PATENT OFFICE.

LEROY A. FARNHAM, OF LAINGSBURG, MICHIGAN.

GARMENT-HANGER.

SPECIFICATION forming part of Letters Patent No. 663,264, dated December 4, 1900.

Application filed May 28, 1900. Serial No. 18,262. (No model.)

To all whom it may concern:

Be it known that I, LEROY A. FARNHAM, a citizen of the United States, residing at Laingsburg, in the county of Shiawassee and State of Michigan, have invented certain new and useful Improvements in Garment-Hangers; and I do declare the following to be a full, clear, and exact description of the invention, such as will enable others skilled in the art to which

10 it appertains to make and use the same.

This invention relates to garment-hangers; and it has for its object to provide a simple, durable, and comparatively inexpensive device adapted to be firmly clamped to the garment, so that the latter may hang naturally therefrom, and thus avoid the creasing caused when the garment is folded; and it consists of the parts and combinations of parts hereinafter described and claimed.

20 In the accompanying drawings, forming a part of this specification, Figure 1 is a perspective view of my improved garment-hanger, showing it in its open or unclamped position; and Fig. 2, a side elevation showing the device in position on a pair of trousers.

Similar letters refer to similar parts in both the views.

Referring to the drawings, A represents the hanger, which is formed of a single piece of stiff metal and preferably of spring-metal wire or rod.

In carrying out my invention I bend one end of the wire or rod, which end will hereinafter be designated the "locking member" 35 a, at its extremity, as at b, for a purpose to be described, and at a suitable distance from said bent end I form one or more coils c in the wire or rod, the bending or forming of the coils being such that the locking member

40 a extends therefrom in an inclined line, so that it normally stands at an angle to the body member d. The body member d extends in a straight line from the coil c for nearly the whole length of the locking mem-

45 ber a, and is then bent downwardly to a U shape to form the retaining-loop E for the end of the locking member, and is again bent in a horizontal line at right angles to loop e to form the guard-loop f for the extreme end 50 of the locking member a, thus preventing the projecting end of said member a catch-

ing into other garments which may be hung near it. The wire or rod is carried from the loop f back along the body member d to the center of the latter, where it is bent around 55 the same, as at g, and is then carried in a vertical line at right angles to said body member for any desired distance, and is then bent to form the hook h, whereby the hanger may be suspended from a rod or pole or a clothes-hook. The object of bending or curving the extremity of the locking member at b is to bring the said member a when its end is engaged in loop e to the plane of the body member, as shown in Fig. 2, whereby the garment 60 65 may be evenly clamped between said members a and d.

While I have shown the device as applied to a pair of trousers, it may be applied to other garments, such as women's skirts, and 70 to other articles of personal wear or personal use and may be used to display such articles in shops.

Having thus described my invention, what I claim as new, and desire to secure by Letters 75 Patent, is—

A garment-hanger formed of a single piece of wire or rod consisting of a locking member having a downwardly curved or bent end, a vertically-arranged coil formed at one end 80 of said locking member, a body member extending from said coil and having a retaining-loop at right angles thereto, and a guard-loop at right angles to said retaining-loop, said guard-loop being arranged in the same 85 horizontal plane as the body member and said wire or rod continuing back from said guard-loop along the body member and being bent around the center of the same and extending at right angles thereto and terminating in a hook, said body and locking members lying close together in the same horizontal plane when the end of the latter is caught in the retaining-loop, whereby the garment 90 may be clamped therebetween.

95 In testimony whereof I affix my signature in presence of two witnesses.

LEROY A. FARNHAM.
